MULTIPLE PUNCH

Allan O. Marsh, Los Angeles, Calif.

Application September 17, 1946, Serial No. 697,504

1 Claim. (Cl. 164—91)

1

This invention relates to paper punches, and more particularly to an improved actuating mechanism for actuating the punch rods employed therein.

While there have hitherto been proposed multiple punches of a type operating off a gang operating rod by engagement of a member in a slot formed in the rod, the punches of this type have not been entirely satisfactory inasmuch as they have employed a milled notch milled in one side of the engaging punch rod. This milled notch has caused the punch rods to bind with the operating rod in the event of any rotation or displacement of the punch rod. Furthermore, the milling of the notches is an expensive operation.

It is therefore one object of this invention to provide a multiple punch of the type described employing an improved actuating mechanism.

It is a further object of this invention to provide an actuating mechanism for a multiple punch employing turned recesses on the punch rods providing an engaging shoulder for cooperating with the gang operating rod.

It is a further object of this invention to provide a multiple punch of the type described which, by reason of the annular groove in the actuating head, avoids binding thereof in the event said head becomes twisted.

Further objects and advantages appear from the annexed specification in which:

Figure 1 is a perspective view of a device embodying the invention; and

Figure 2 is a section taken on the line 2—2 of Figure 1.

Referring more particularly to the drawings, there is shown a multiple punch including a base 1 and a plurality of punch heads 2. The heads 2 are mounted within a slide recess 13 in the base 1 and are held in their adjusted position by means of knurled bolts 14 and nuts 18 acting to clamp a shoulder 15 formed on the heads 2 to the base 1. The nuts 18 are hexagonal in form and are prevented from rotating by the depending ribs 19 in the lower side of the base. Within the punch heads 2 are slidably mounted punch rods 3 yieldably urged toward retracted position by means of springs 4. The springs 4 are seated in the bottom of a bore 20 formed within the punch heads 2, and the upper ends of the springs resiliently press against the lower edge of a shoulder 11. The shoulder 11 forms a bearing section slidably engaging the walls of the bore 20 and serving to align the punch rod 3. Another bearing section 12 is formed at the upper end of the

2

punch rod as indicated. A gang operating rod 5 is journaled in the respective heads 2 and provided with an operating handle 6. The operating rod 5 is formed with a milled groove 7 forming an actuating shoulder adapted to engage the operating shoulder 9 formed on the punch rods 3 as hereinafter described.

In forming the completed punch rod 3, the rod 3 is placed in a suitable machine tool and the section 10 is turned therein to provide clearance for the rod 5. The rod 3 is also turned as at 10^a to provide the completely annular operating shoulder 9. In order to hold the paper square within the paper receiving slots 16 of the heads 2, an adjustable paper guide 17 may be provided which is supported on the base 1 in advance of the punches 2 as indicated.

Heretofore it has been the practice in constructing this type of multiple punch to mill a shoulder somewhat similar to the shoulder 9 transversely of one edge of the rod 3. The result has been that, if the punch rod 3 is twisted in the head 2, it will jam the shoulder against the operating rod 5 either destroying the shoulder or jamming the punch. By turning the rods 3 as is contemplated in this invention, not only is an expensive milling operation avoided, but a completely annular shoulder as well as the completely annular turned portions 10 and 10^a are provided with the result that no matter how the punch rods 3 may twist in the machine, it is impossible for the shoulder to jam in the groove 7 formed in the gang operating rod 5.

It should be carefully observed that the longitudinally extending grooved portion 7 is triangularly shaped with the apex 7A of such grooved portion lying substantially on the longitudinal axis of the operating rod 5, and that such grooved portion is defined by the normally upwardly inclined plane face 7B and downwardly extending face 7C. Likewise, it should be carefully observed that the upper face 9A of the annular shoulder 9 lies on a horizontal plane with the peripheral edge of such surface 9A normally engaging the plane face 7B on a line contact. This line contact provided between the face 7B and the upper edge of the annular shoulder 9 is of importance in that, as a consequence thereof, the punch rod 3 is relatively free to turn about its own axis when and as it is moved downwardly upon rotation of the operating rod 5 about its axis, which axis corresponds substantially to the apex of the triangularly shaped grooved portion 7.

While there has been described what is at present considered a preferred embodiment of the invention, it will be understood that various changes and modifications may be made therein without departing from the essence of the invention that is intended to cover herein all such changes and modifications as come within the true scope and spirit of the appended claim.

I claim:

In a punch construction of the character described, an operating rod having an actuating handle, a triangularly shaped longitudinally extending grooved portion in said rod, a punch head, said punch head having a bore therethrough, a punch rod mounted in said bore, said 10 punch rod having formed thereon a pair of spaced shoulders, said spaced shoulders being spaced by two converging conical sections, a spring recessed within said head and having one of its ends abutting said head and the other one 20 of its ends abutting one of said shoulders, said grooved portion cooperating with the other one of said shoulders in all angular positions of said rod and encompassing the same to confine said other shoulder within said grooved portion, said 25 rod being journaled in said punch head, the

upper surface of said other annular shoulder being in a horizontal plane and having its peripheral edge in line contact with an upwardly inclined plane face of said triangularly shaped grooved portion, actuation of said handle resulting in rotation of said rod about its axis, whereby due to said line contact, the punch rod is relatively free to rotate about its axis simultaneously with its resulting longitudinal movement.
